ASH TRAY

James Kenneth Dodge and Martin William
Johnson, Albany, Calif.

Application October 20, 1941, Serial No. 415,724

6 Claims. (Cl. 206—37)

Our invention relates to a receptacle and more particularly to a portable receptacle for use as an ash tray.

Among the objects of our invention are to provide a novel and improved ash tray—

(1) Which is capable of being carried around on the person, without danger of leakage of contents therefrom;

(2) Which, when not in use, is capable of being sealed against spilling of contents;

(3) Which may be readily emptied when desired, without danger of soiling one's hands or clothing;

(4) Which may conveniently be suspended for use from some article of furniture or the like.

Additional objects of our invention will be brought out in the following description of the same taken in conjunction with the accompanying drawing, wherein—

Figure 1 is a view in perspective of our improved ash tray in closed condition;

Figure 2 is a view in perspective of the same device open for use;

Figure 3 is a front view in section of the device of Figure 2;

Figure 4 is a side view in section taken along the line 4—4 of Figure 3;

Figure 5 is a view in section taken along the line 5—5 of Figure 3.

Referring to the drawing above described, the device comprises a receptacle 1 preferably, though not necessarily, rectangular in cross section, having a top wall 3, a bottom wall 5, side walls 7 and 9, and end walls 11 and 13, respectively. The end wall 13 is hinged to provide an openable cover having a catch 15 for engagement with a depression 17 in the top wall to hold the same in closed position. In the top wall of the receptacle, we provide a substantial opening 19 through which to introduce ashes or the like, into the receptacle, the wall being depressed about the opening to receive a frame 21 of wire to facilitate engagement by and provide a sealing fit with a cover 23. The cover is preferably hinged along one side and provided with a catch 25 for latching with the wire frame at the opposite side of the opening.

The receptacle is fitted with a transverse partitioning wall 27 having depending side walls 29 and 31 in close fitting engagement with the side walls 7 and 9, respectively, of the receptacle, this partition having a portion removed therefrom to form an opening 33 of substantially the same size and in alignment with the opening 19 in the top wall of the container. The partition-

ing wall divides the container into upper and lower sections 35 and 37. In the upper section we provide longitudinal walls 39 and 41 in spaced relationship to the side walls of the container, each of these walls having an offset 43 and 45, respectively, to one of the side walls of the container, which forms with the partition 27 a guide groove extending substantially the full length of the receptacle along each side thereof.

These guide grooves receive a sliding gate 47 which, in one position, is adapted to close the opening 33 in the partition wall and, in another position, will expose such opening. The closing position of the gate is determined by a depending wall 49 closing the space between the far edge of each of the aligned openings 19 and 33 and serving as an abutment for the sliding gate when urged to its closing position.

The gate is biased to this closing position by a coiled spring 51 lying within the space defined by the longitudinal wall 39 and the side wall 7 of the container. This spring is anchored at the far end of the container and preferably to the end wall 11 thereof, while its other end is connected to the sliding gate. Such connection is preferably effected by a slidable anchoring strip 53 joined to the gate by a link 55 straddling the upper edge of the wall 39 which has been cut down for the purpose of permitting of such sliding movement.

When the sliding gate is forced to its open position, the tension on the spring will be increased, and to hold the gate in its open position against such increased tension, a holding means in the form of a spring clip 57, which is adapted to engage the free edge of the gate, is provided. This engaging clip is preferably attached to a wall 59 which depends from the top wall of the container to about the level of the guides so as not to interfere with the proper sliding of the gate.

In the use of the receptacle as an ash tray, the closure 23 in the top wall will first be opened, and then the sliding gate will be forced back to its open position, whereby exposing the interior of the receptacle for the reception of ashes, or the like. When substantially full, the sliding gate may be released and the closure urged to its closing position, which makes the receptacle substantially sealed against loss of any of its contents.

Now when it is desired to empty the same, this may be very conveniently accomplished by snapping open the hinged end wall 13 and the entire contents may be emptied from the receptacle, without danger of soiling the hands or clothing.

The receptacle is preferably of such small di-

mensions as to conveniently be carried around in the pocket, and by reason of its construction, the same may be carried around without danger of leakage of any of the contents therefrom.

To enlarge its field of use, we provide a pivotally secured supporting hook 61 to the underside of the closure which, when swung away from its position adjacent the cover, may be employed in suspending the receptacle from furniture or the like, and more particularly from the back of a chair, and when so suspended, the receptacle will be maintained in horizontal position ready for use. This supporting hook may preferably be formed of wire which gives it a certain amount of resiliency, whereby the hook portion, if made sufficiently large to engage the gate 41 when the cover 23 is urged to its closing position, will impart to the supporting hook the added function of a cover spring. Thus, when the cover catch is freed, the supporting hook 61 will cause the cover to spring open.

If it is desired to reduce the depth of the receptacle to the extent of eliminating the space above the partitioning wall 27, this can be readily effected by providing a container of less depth, and placing the partitioning wall closely adjacent the top wall of the container. The partitioning wall will then have its side walls 29 and 31 turned under to form guides for the reception of the sliding gate 47, and the gate spring 51 will then be supported below one of these guides. With such change, no space will be available for the spring supporting hook 61 and the same will, therefore, have to be eliminated.

While we have described one embodiment of our invention in detail, the same is susceptible to various changes without departing from the scope of the invention, and we accordingly do not desire to be limited in our protection to such details, except as may be defined by the appended claims.

We claim:

1. A pocket ash tray or the like comprising a container having a top wall opening and an end opening, independently openable closures for both said openings, a slidable gate normally positioned beneath said top wall opening closure, said gate normally sealing communication to the interior of said container via said top wall opening and adapted to be slid sufficiently to expose said opening to the interior of said container, and a hanger spring affixed to the underside of the closure for said top wall opening.

2. A pocket ash tray or the like comprising a container having an upper wall and end walls, one of said end walls including an openable end closure for said container, said upper wall having a passage therethrough into said container, a closure for said passage secured to said container, a gate within said container normally sealing said passage, and means permitting movement of said

gate between a position in line with said upper wall opening beneath said upper wall closure and a position exposing said opening to the interior of said container.

- 5 3. A pocket ash tray or the like comprising a
container having an upper wall and end walls, one
of said end walls constituting an openable end
closure for said container, said upper wall having
an opening therein, a closure for said opening
10 secured to said container, a gate within said con-
tainer normally sealing communication via said
upper wall opening to the interior of said con-
tainer, and means slidably supporting said gate
and permitting movement thereof between a posi-
15 tion in line with said upper wall opening beneath
said upper wall closure and a position exposing
said opening to the interior of said container.

4. A pocket ash tray or the like comprising a
container having an upper wall and end walls,
20 one of said end walls constituting an end closure
for said container, said upper wall having a pas-
sage therethrough into said container, a gate within
25 said container normally sealing said pas-
sage, and means slidably supporting said gate and
permitting movement thereof between said pas-
sage blocking position and a position exposing
said passage to the interior of said container.

5. A pocket ash tray or the like comprising a
container having an upper wall and end walls,
30 one of said end walls constituting an openable
end closure for said container, said upper wall
having a passage therethrough into said con-
tainer, a closure for said passage hingedly secured
35 to said container and including a hanger spring
affixed to the underside thereof, a gate within said
container, and means slidably supporting said gate
and permitting movement thereof between a posi-
tion blocking said passage beneath said upper wall
40 closure and a position exposing said passage to
the interior of said container, said hanger spring
being compressed between said gate and its sup-
porting closure when both said gate and closure
are in closed position, whereby said closure will
45 spring open when released and expose said spring
for use as a hanger for said ash tray.

6. A pocket ash tray or the like comprising a
container of a size adapted to be carried in one's
50 pocket, said container having a top wall opening
and an end wall opening, walls depending from
the edges of said top wall opening and extending
part way into said container, a gate in said con-
tainer, means slidably supporting said gate in
55 substantially sealing engagement with said de-
pending walls and permitting movement of said
gate from said sealing position to a position
exposing said opening to the interior of said
container.
